UNITED STATES PATENT OFFICE.

ROBERT CANNAN, OF BROOKLYN, NEW YORK, ASSIGNOR OF ONE-HALF TO
PATRICK KENNEDY, OF BROOKLYN, NEW YORK.

COTTON-HARVESTER.

SPECIFICATION forming part of Letters Patent No. 723,985, dated March 31, 1903.

Application filed October 14, 1901. Renewed September 4, 1902. Serial No. 122,081. (No model.)

To all whom it may concern:

Be it known that I, ROBERT CANNAN, a citizen of the United States, residing in the city of New York, borough of Brooklyn, county 5 of Kings, and State of New York, have invented certain new and useful Improvements in Cotton-Harvesters, of which the following is a specification.

This invention relates to the class of cotton harvesters or pickers which employ a wheeled vehicle carrying and driving two upright drums armed with radially-projecting picker-stems. The drums are carried along by the vehicle and rotated, and the cotton-plants in the row pass between them.

One of the more important features of the present invention reside in the construction and operation of the picker-stems and in the means for stripping the cotton therefrom.

The invention will be fully described hereinafter with reference to the accompanying drawings and its novel features carefully defined in the claims.

In the drawings which illustrate embodiments of the invention, Figure 1 is a sectional side elevation of the harvester. Fig. 2 is a plan with the body and a part of the frame removed to better disclose the mechanism. Fig. 3 is a front elevation. Fig. 4 is a horizontal section of the drum on a relatively large scale, and Fig. 5 is a face view of one of the strippers. Fig. 6 is a vertical section of the drum on the same scale as Fig. 4. Fig. 7 is a somewhat diagrammatical plan view showing the two drums in the relative operative positions and the forms of the cams which operate the strippers. Figs. 8, 9, and 10 are views illustrating in detail the construction of the picker-stems, clutches, and strippers. Figs. 11 and 12 are detached plan views of the radially-slotted heads of the drum, the latter showing one-half of the upper head.

1 designates in general the frame of the vehicle.

2 designates the hind wheels, fixed on the rotatively-mounted axle 3.

4 designates the front wheels, rotative on the arms of a bent axle—or, in other words, 50 the axle-arms are rigidly secured by suitable means to a fifth-wheel 5, which is rotatable

for steering about a bearing in the frame and which may be turned for steering by means of gear-wheels 6 and 7 and a hand-wheel 8. There is nothing especially novel in this construction. 55

As herein shown, the rear axle is driven for propelling the vehicle and driving the picker-drums by a motor 9, (illustrated somewhat diagrammatically in Figs. 1 and 2,) as 60 any form or kind of known motor may be employed. As shown herein, the motor drives a counter-shaft 10, through gear-wheels 11 and 12, and the rear axle is driven from the shaft 10, through sprocket-wheels 13 and 14 65 and a chain 15. The driver or operator controls the movement through a handle 16 and suitable intermediate mechanism, such as is commonly employed for this purpose.

What is described above simply provides 70 for the propulsion and guiding of the vehicle, and the means employed for picking the cotton fiber from the open bolls of the row of plants as the vehicle moves along will now be described.

Under the frame 1 of the vehicle, at a suitable distance apart laterally, are the picking-drums, (designated each as a whole by D.) These drums have their axes upright, and they are rotative in strong frames 17 under the 80 frame 1. Fig. 2 shows perhaps most clearly the mechanism for driving the drums D from the counter-shaft 10. On the latter is a sprocket-wheel 18, which drives a sprocket-wheel 19 through a chain 20. The wheel 19 is on a cross-shaft 21 in the vehicle-frame, and it carries two bevel-wheels 22, which gear, respectively, with similar wheels 23, fixed on the drums. This rotary motion is imparted to the drums in the direction indicated by the curved arrows in Fig. 2 as the vehicle moves in the direction indicated by the straight arrows in said figure. As the drum rotates it carries about with it radially-projecting picker-stems arranged in horizontal tiers. These stems are 90 provided with teeth to engage and gather the cotton fiber about the stems, and mechanism is provided for imparting rotation to said stems. This mechanism will now be described with especial reference to the detail 100 views Figs. 4 and 6.

Rotatively mounted in the axis of each

drum D is a shaft 24, and these shafts are rotated by bevel-wheels 25 25 on said shafts and on a cross-shaft 26, driven from the counter-shaft 10 through sprocket-wheels 27 5 and 28 and a chain 29, as seen in Figs. 1 and 2. On the shaft 24 inside of the drum are secured a series of bevel-wheels 30, Fig. 6, one for each tier of picker-stems, and this wheel gears with bevel-pinions 31 on the respective journals of the picker-stems. In the detail views the picker-stems are each designated as a whole by the letter S. As the picker-stems are presented to the plants in the row they are exposed, so that their teeth 15 may operate; but as the drum rotates a stripper is pushed out over them to strip off the accumulated cotton fiber. In Figs. 4 and 6 the operative side of the drum is at the right and the stripping side at the left. In order 20 to make the construction of the stripping mechanism clearly understood, a description of the construction of the drum D will be required, with especial reference to Figs. 4, 6, 7, 11, and 12.

25 The lower head 32 and the upper head 33 of the drum D (seen detached, respectively, in Figs. 11 and 12) are connected together by an upright prismoidal body 34, the form of which is indicated in dotted lines in Figs. 11 30 and 12. Mounted in radial slots 35 in the heads of the drum, exterior to the body 34, are slides 36, each corresponding slide above and below being connected by an upright bar or stave segment 37. The upper and 35 lower heads of the drum have journals which turn in bearings formed in fixed cams 38, in the grooves of which play antifriction studs or bowls 39 on the respective slides 36. Fig. 7 shows the form of the cam-grooves and also 40 shows how the upright segments 37 when drawn in come together edge to edge, like staves, to form a cylinder. The journals 40 of the respective picker-stems S have bearings in the wall of the drum-body 34, and the body 45 41 of the picker-stem, which is or may be cylindrical, plays through a stripper 42, which is splined on the said stem-body, so that when the body rotates it rotates the stripper also. Each stripper has a collared bearing in a segment or stave 37 and moves in and out radially with said stave when the latter is actuated by the cams. Fig. 5, which represents a face view of a stripper, shows the four radial slots 43 in it provided for the passage of the four 50 rows of inclined teeth on the picker-stem. Fig. 8 includes several views illustrating the construction of the body 41 of the said stem. This body is a cylinder with a series of longitudinal keeper-grooves 44 in its surface to 55 receive the strips 45, provided each with a series of teeth 46. When the strips 45 have been inserted, the cap 47 is screwed into or onto the outer end of the body. The journal 40 of the stem S is in rotation constantly; 60 but it is rotatable in the body 41, except when the latter is clutched to it, as will be ex-

plained. In the body, Fig. 8, is a longitudinal keyway or groove 48, with which engages a key 49 on the rear or inner face of the stripper 42, as seen in Fig. 9, which is a rear view 70 of the latter. This construction compels the stripper and the body 41 to rotate together. On the journal 40 is secured a collar 50, on which is splined a sliding clutch member 51, backed by a spring 52. This clutch member 75 has on its outer face (seen in Fig. 9) two or more lugs 53, which when the stripper 42 is drawn in, as at the right in Fig. 6, engage corresponding lugs 54 on the inner face of the stripper, and thus drive the latter, and 80 through it the body 41; but when the stripper moves radially outward over the body to strip off the accumulated cotton fiber from the body the clutch members are at once disengaged and the stripper and body of the 85 picker-stem cease to rotate. The object of this construction is of course to rotate the operative portion of the stem only during the picking operation and to arrest such rotation during the stripping operation. The inclination of the teeth 46 outward causes the cotton thereon to be pushed off the teeth as the latter enter the slots in the conical face of the strippers.

As the cotton fiber which has accumulated 95 on the stems of the respective drums is stripped therefrom it is taken up by conveyers, one at each side of the vehicle, and carried up to the proper level for discharge and there freed from the conveyers. It is not new, 100 broadly, to carry up harvested substances or fibers from one level to another by elevating-conveyers, and this is not broadly claimed; but the specific construction of the conveyer has some novel features which will now be described. 105

55 designates the upper cross-shaft of the conveyers, driven from the cross-shaft 26 through the medium of a chain 56 on suitable sprocket-wheels carried by the respective 110 shafts.

57 designates the upper pulley of the conveyer on the shaft 55, and 58 the lower pulley. Over these is the conveyer-belt 59, provided with teeth 60 to gather and carry up 115 the cotton stripped from the picker-stems S. The rear side of the conveyer-belt moves upward with its load of cotton.

The conveyer-belt is inclosed in a stripper-casing 61, and the upright portion of this casing at the operative side of the belt—namely, the side which moves upward and which is at the left in Fig. 1—is in close proximity to the belt at its lower end, where it is longitudinally slotted up to a predetermined 125 height to provide a way for the conveyer-teeth, of which there may be two or more rows. Fig. 2 shows the two slots 62 in this side or face of the casing, which inclines or diverges from the conveyer-belt above, so 130 that as the teeth move upward along the slots the casing gradually strips the cotton from

the teeth, the fiber leaving the teeth at the point where the latter draw into the casing in their upward travel. This point may be at any level desired and will be inside of the 5 box-like body B on the vehicle-frame. This body is seen partly broken away in Fig. 1, and its outline in plan is indicated by dotted lines in Fig. 2. Where the cotton carried up to the conveyer enters the bottom of the 10 body B there is a suitable aperture a. (Seen in Fig. 1.) The conveyer where it passes through the interior of the body B will be suitably inclosed in a known manner, and the driving-belt of the conveyer will also be 15 inclosed in a casing. This is a mere matter for an ordinary workman and will require no special description. At the lower end or foot of the conveyer there is or may be a receiver or catcher 61^a (seen best in Fig. 2) to catch 20 any cotton that may fall from the picker-stems D and not be fairly caught at first by the teeth of the conveyer.

In front of the body B and on the frame of the vehicle is a seat s for the driver or motor-man.

Figs. 1 and 2 show gathering devices placed under the frame of the vehicle at the front part to embrace or gather the cotton-plants of the row and present them to the picking-drums. Carried by the running-gears under the front of the body are two upright shields 63 63, one at each side. These turn with the fifth-wheel about the king-bolt when the front axle is turned for steering. Back of these 35 plates or shields are two converging shields or plates 64, which form normally or when the vehicle is moving straight ahead continuations of the gathering shields or plates 63.

Obviously the vehicle may be drawn by 40 horses, as in other forms of these harvesters, in which case the hind wheels of the vehicle would be made to serve as ground-wheels for driving the drums, picker-stems, and conveyers.

45 My construction of the picker-stems provides for conveniently changing the tooth-bearing strip 45, so as to change the length, form, or character of the teeth to suit circumstances, and it also provides for the removal 50 of the bodies 41 of the lower tiers of picker-stems in the drum in case the conditions of the harvest are such that only the upper stems are required.

In Figs. 1 and 3, 65 designates diagrammatically the boiler for supplying steam to the engine 9, and 66 designates in the same manner a holder for oil, as fuel, and water of the boiler.

Having thus described my invention, I 60 claim—

1. A cotton-harvester having an axially-rotating picker-stem provided with one or more rows of teeth, and a stripper embracing said stem and slidably longitudinally along the 65 same, said stripper being splined on the stem

and having a radial slot or slots for the passage of the teeth on the stem in stripping.

2. A cotton-harvester having an axially-rotating picker-stem provided with one or more longitudinally-extending rows of teeth, a 70 stripper embracing said stem and rotating therewith, and means for moving said stripper over said stem for stripping the collected cotton therefrom.

3. A cotton-harvester having a plurality of 75 axially-rotatable picker-stems, each having a longitudinally-extending row or rows of teeth, means for rotating said stems, rotatively-mounted strippers embracing the respective stems and splined thereon so as to rotate 80 with the stems, means for operating the strippers and stems relatively to strip the cotton from the stems, and means for arresting the rotation of the stems during the stripping operation.

4. A cotton-harvester having a drum rotating on an upright axis, a plurality of radially-extending, axially-rotating picker-stems mounted in said drum, strippers splined on the respective stems and slidably longitudinally thereon, upright staves in which said strippers are rotatively mounted, said staves being slidable radially in the drum, and stationary cams which operate said staves and strippers radially as the drum rotates. 85

5. In a cotton-harvester, the picker-stem having a body 41, grooved longitudinally to receive the tooth-bearing strips 45, the said strips, the cap 47, closing the end of the body, and the journal 40, rotative in the body 41. 90

6. In a cotton-harvester, the combination with the rotating journal of the picker-stem, the body of the said stem provided with longitudinal rows of teeth, said body being rotatable on the journal, the radially-slotted 105 stripper splined on the body of the stem, and provided with a lug or lugs on its inner face, and a clutch member on and rotatable with the journal of the picker-stem, said clutch member having on its outer face a lug or lugs 110 to engage the lugs on the stripper, of means for moving said stripper to and fro along the body of the picker-stem.

7. A cotton-harvester having running-gears under its front end which turn about a 115 king-bolt in steering, two picker-drums back of the front axle and suspended from the main frame, and a gathering device consisting of two upright shields 63, mounted on the front running-gears, and two converging 120 shields 64, back of the front shields, substantially as set forth.

In witness whereof I have hereunto signed my name, this 11th day of October, 1901, in the presence of two subscribing witnesses.

ROBERT CANNAN.
